UNITED STATES PATENT OFFICE.

SAMUEL B. FLEMING, OF CHICAGO, ILLINOIS.

COAL-DISTRIBUTING APPARATUS.

No. 924,332.

Specification of Letters Patent.

Patented June 8, 1909.

Application filed June 6, 1907. Serial No. 377,613.

To all whom it may concern:

Be it known that I, SAMUEL B. FLEMING, a citizen of the United States, residing at Chicago, in the county of Cook and State 5 of Illinois, have invented certain new and useful Improvements in Coal-Distributing Apparatus, of which the following is a specification.

This invention relates more particularly 10 to apparatus used for distributing coal on the long fire banks which are formed in burning ballast or the like.

In burning ballast, a fire is built on a clay bank alongside of a railway track and then 15 coal and clay are alternately piled on the bank. The clay is ordinarily put in place by means of suitable mechanism operated from cars running along the track, and heretofore the coal has usually been conveyed by means of a conveyer, to a platform 20 out over the fire, and then distributed by means of hand shovelers. This shoveling is difficult and arduous, as the shovelers are over, or adjacent to the fire and are subjected to the heat and smoke arising from 25 the bank.

I am aware that it has been heretofore proposed to distribute coal by mechanical means; but so far, no practicable plan seems 30 to have been devised.

It is the object of this invention to provide simple and efficient mechanical means for distributing the coal onto the bank without the aid of shovelers. I accomplish this 35 by means of the mechanism which is shown in the accompanying drawings and which is fully described and claimed hereinafter.

In the drawings: Figure 1 is a partially diagrammatical end-view of a car provided 40 with my improved distributing apparatus; Fig. 2 is a top-plan view of the distributing apparatus, the conveyer flights and other parts being omitted for convenience in illustration. Fig. 3 is an end-view of the conveyer; and Fig. 4 is a detail showing the distributing chute. Fig. 5 is an enlarged detail showing the outer portion of the conveyer; and Fig. 6 is a detail showing the arrangement of the eccentric box, gear and rack viewed from the opposite direction 45 from Fig. 5.

As shown in the drawings, 5 represents a support, preferably, a car mounted to run 50 along the track 6. This car is provided with a hopper 7 adapted to discharge through a gate 8 onto a conveyer distribut-

ing apparatus 9. This conveyer is pivotally supported in the car so that the outer end may be raised and lowered, as by means of a cable 10 which passes up and over a sheave 60 11 on the mast 12 and then down to a windlass 13 mounted on the car in any convenient position. The conveyer preferably consists of two side-beams 14—14, having a stationary trough 15 secured therein and extending 65 from the rear end to about the center of the conveyer. A second movable or telescoping trough-section 16 is also provided at the outer end of the conveyer, this trough being supported on strips or guides 17 which run 70 on guideways on the beams 14. These guideways may comprise strips, but I prefer to use small rollers as shown at 18—18. This outer or telescoping section slides under the inner or rigid section, as shown particularly in Figs. 2 and 3. At the outer end of the movable section 16 is a distributing chute 19 which is provided with deflectors 20—20 in order to spread the coal over a considerable area. The coal is moved by 80 means of flights 21—21 mounted on a suitable chain or chains 22 passing over sprocket-wheels 23 and 24 mounted on shafts 25 and 26 at the ends of the beams 14.

The driving and operating mechanism is 85 as follows: The engine or power shaft 27 is provided with a sprocket-wheel 28 which drives a chain 29 which in turn drives a sprocket-wheel 30 mounted on a shaft 31 at about the center of the conveyer. A second 90 sprocket-wheel 32 on the shaft 31 drives a second chain 33 which in turn drives a sprocket-wheel 34 on the shaft 26 and thereby operates the conveyer proper. In order to operate the movable or telescoping trough 95 16 so that it may be driven in either direction, I have provided a second shaft 35 adjacent to the shaft 31 and driven therefrom by means of gears 36—37. At the opposite ends of the shafts 31 and 35 are friction 100 wheels 38 and 39 which are adapted to engage, at times, with a friction wheel 40 mounted on an intermediate shaft 41. This intermediate shaft is provided at its outer end with an eccentric box 42 and has an 105 operating lever 43 whereby the eccentric may be turned to throw the wheel 40 from a central position into engagement with either of the wheels 38 or 39, as desired. As the wheels 38 and 39 turn in opposite directions, 110 it is obvious that a reverse movement may thus be given to the shaft 41. The shaft 41

is provided with a pinion 44 which engages with a rack 45 on the bottom of the telescoping trough 16, so that when the shaft is turned in one direction the trough will be moved outward, and as the shaft is turned in the opposite direction the trough will be moved inward or toward the car.

An operator's platform 46 is provided adjacent to the lever 43, so that the operator 10 may stand out on the conveyer and operate the movable section of the trough and thereby distribute the coal evenly across the conveyer. The position of this operator's platform is one of importance, inasmuch as it is 15 necessary for him to be so situated as to be able to see the fire or see under the smoke in order to properly distribute the coal; this position also enables him to be observed by the engineer, so that the distributing car can 20 be moved along the track according to the operator's signals so that the coal will be evenly distributed along the bank.

It is desirable that the operator be able to control the amount of the coal delivered to 25 the conveyer, and for this purpose an operating rod 47 is provided for controlling the gate 8.

The operation of the apparatus will be readily understood from the foregoing description. The coal, being discharged from 30 the hopper 7 into the trough 15, is moved along by means of the conveyer flights until it reaches the end of the movable section 16, when it slides down over the discharge chute 35 19 and is deflected for a considerable distance to each side of the conveyer; then, as the operator moves the section 16 back and forth, the coal is evenly distributed across the bank.

40 Various changes in the details of construction may readily suggest themselves as coming within the scope of my invention, therefore I do not wish to be limited to the exact form of apparatus shown herein, but

45 What I claim and desire to secure by Letters Patent is:—

1. In an apparatus of the character described, the combination with means for conveying the fuel, of a spreading discharge 50 chute having diverging sides and having a plurality of deflectors projecting upwardly from the bottom of said chute for spreading the coal evenly.

2. In an apparatus for distributing coal, 55 the combination with a framework provided with a stationary trough and a movable trough adapted to coöperate with a single movable conveyer mechanism, of substantially constant length and means for re-

ciprocating said movable trough, the arrangement being such that the discharge end of the movable trough approaches toward, and recedes from the outer end of the conveying mechanism as said trough is reciprocated.

3. In a coal distributing apparatus for ballast fires, the combination of a car, a lateral conveyer mounted in said car, a movable bottom-trough along which the coal is moved by the conveyer flights at the outer 70 end of said conveyer, and a rack and pinion mechanism for moving said trough.

4. In a coal distributing apparatus for ballast fires, the combination with a supporting car, of a lateral conveyer, a movable 75 discharge and spreading device for said conveyer, for spreading the coal evenly over the fire, operating means for moving said discharge device, said means being located at about the center of the conveyer, and an 80 operator's platform adjacent to said operating means.

5. The combination of a car, a hopper in said car, a lateral conveyer for conveying coal from said hopper, a movable distributing device at the outer end of said conveyer, means for moving said distributing device, said means being provided with a controlling lever at about the center of the conveyer, an operator's platform adjacent to 90 said controlling lever, and means whereby said operator can regulate the amount of coal discharged into said conveyer.

6. In a conveyer, the combination with a rigid trough-section, of a telescoping 95 trough-section, a chain or chains with flights for moving material along said trough sections, guideways for said telescoping section, a rack on said telescoping section, a pinion engaging with said rack, a shaft on 100 which said pinion is mounted, and means for turning said shaft in either direction.

7. In a conveyer, the combination with a stationary trough-member, of a telescoping trough-member, said telescoping member being provided with a rack, a pinion engaging with said rack, a shaft on which said pinion is mounted, a pair of shafts adjacent to said pinion shaft and turning in opposite directions, friction wheels on each of said 105 shafts, and means for throwing the friction wheel on the pinion shaft into engagement with either of the other wheels when desired.
